UNITED STATES PATENT OFFICE.

FRANK N. OSBORNE, OF NEW YORK, N. Y., ASSIGNOR TO THE GORHAM MANUFACTURING COMPANY, OF PROVIDENCE, RHODE ISLAND.

DESIGN FOR A BRUSH-BACK.

SPECIFICATION forming part of Design No. 28,021, dated December 14, 1897.

Application filed October 4, 1897. Serial No. 654,081. Term of patent 7 years.

To all whom it may concern:

Be it known that I, FRANK N. OSBORNE, a citizen of the United States, residing at New York, in the county of New York and State of New York, have invented and produced a new and original Design for a Brush-Back or Similar Article, of which the following is a specification, reference being had to the accompanying drawing, forming a part thereof.

10 The drawing is a view of the back of a hair-brush.

15 The leading feature of my design consists in the raised and scrolled beads extending the length of the handle and on opposite sides of the brush-back, inclosing what is known in the art as "honeysuckle" ornaments and tendrils, partially entwined with the scrolled beads.

20 In the drawing, A indicates the handle, and B the back, of the brush. At the end of the handle the foliated ornament 3 extends radially from a central semispherical boss, and from each side of the foliated ornament 3 extend in curves parallel with the margin of 25 the handle the raised beads 4, terminating at the junction with the back in the scrolls 5. The conventional honeysuckle ornament 6, much used in Greek architecture, extends from the foliated ornament 3 upward between 30 the beads 4, and from this extend upward the foliated scrolls 7, entwined around the beads 4, having a raised rose 8 on each side

and the rose 9 at the apex of the foliated scroll. The scrolls 5 of the beads 4 support an oval convex jewel, from each side of 35 which extend upward the scrolls 10, 10, inclosing the honeysuckle ornament 11.

The upwardly and then outwardly curved raised beads 12, terminating at the lower ends in the foliated scrolls 13, extend on each side 40 of the back and terminate at the upper end in a series of scrolls 14, 14, between which the pendent honeysuckle ornament 15, having on each side the pendent floral ornaments 16, 16, ornaments the space between the beads 45 12. The scrolls 14, 14 are surmounted by the shell ornament 17. On each side of the beads 12 the floral ornaments 18 extend along the outside of the beads and partially inclose the same. 50

It is obvious that the design is adapted for hand-mirrors and similar articles.

Having thus described my newly-produced design, what I claim as new, and desire to secure by Letters Patent, is— 55

The design for a brush-back or similar article herein shown and described.

In witness whereof I have hereunto set my hand.

FRANK N. OSBORNE.
